(57) **CLAIM**

The ornamental design for a luggage with marble patterned design, as shown and described.

DESCRIPTION

FIG. 1 is a front perspective view of a luggage with marble patterned design, showing my new design.

FIG. 2 is a front perspective view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines showing the handles, feet, and wheels are for the purpose of illustrating environmental structure and unclaimed subject matter and form no part of the claimed design.

1 Claim, 7 Drawing Sheets
